UNITED STATES PATENT OFFICE.

FREDERICK RAY, OF SHORT HILLS, NEW JERSEY, ASSIGNOR TO ALBERGER PUMP AND CONDENSER COMPANY, OF NEW YORK, N. Y., A CORPORATION OF NEW YORK.

CENTRIFUGAL, TURBINE, OR SIMILAR PUMP.

1,172,555.

Specification of Letters Patent. Patented Feb. 22, 1916.

Application filed September 24, 1912. Serial No. 722,007.

To all whom it may concern:

Be it known that I, FREDERICK RAY, a citizen of the United States, residing at Short Hills, in the county of Essex and State of New Jersey, have invented certain new and useful Improvements in Centrifugal, Turbine, or Similar Pumps, of which the following is a specification, reference being had therein to the accompanying drawing.

10 My present invention relates to improvements in centrifugal, turbine or similar pumps, and more particularly to that class of such pumps wherein the object is to pump air and produce a vacuum, and where a rotary impeller is employed in combination with an inlet for air, gas or vapor, and an inlet for water or other liquid, all arranged so that the channels between the vanes or blades of the impeller will each receive air 15 and water alternately, so that in each of said channels there will be a succession of air pistons and water pistons that will be driven by centrifugal force outwardly into the casting of the pump where the discharge will 20 be made to the atmosphere against atmospheric or higher pressure.

The object of the invention is to increase the range of the practical application of centrifugal, turbine or similar pumps of the 30 particular class just mentioned; and it consists essentially in a centrifugal turbine or similar pump having an impeller or impellers provided with a multiple arrangement or a plurality of series of vanes or blades, in each of whose channels there is a 35 succession of air and water pistons, and a multiple arrangement or a plurality of fluid injecting nozzles for delivering quantities or plugs of water to the several impeller channels, and whereby the water is caused to expose a greater surface to the air so as to 40 cause a commingling or mixing of the air and water to a certain extent in addition to the formation of the succession of water and air plugs; and it also embraces a centrifugal, 45 turbine or similar pump for pumping water in a continuous stream into the said fluid-injecting nozzles, together with inlet means for the air, so that air plugs will enter the 50 impeller channels between the injected water plugs; and the invention also comprises numerous details and peculiarities in the

construction, arrangement and combination of the various parts, substantially as will be hereinafter described and claimed.

55

In the accompanying drawing illustrating my invention:—Figure 1 is a longitudinal section of my improved centrifugal, turbine or similar pump. Fig. 2 is a partial or broken plan view of the same with the air inlet shown in section. Fig. 3 is a cross section of one series of impeller vanes or blades and one series of water injecting nozzles alined with said vanes or blades.

60

Similar characters of reference designate corresponding parts throughout the different figures of the drawing.

65

1 denotes the main casing of a centrifugal, turbine or similar pump, the same being of the usual form and provided with a discharge passage 2 having an exit to the atmosphere at 3, through which a mixture of air and water from the interior of the pump finds passage to the atmosphere against atmospheric or higher pressure. In the casting 1 is an impeller 4 of the closed type having a hub 5 which is firmly secured to the main engine shaft 6. The impeller 4 is provided with a multiple arrangement of series of vanes or blades 7, between which vanes or blades are the curved passages 8. There may obviously be any number of these series of vanes or blades. In the particular example of mechanism shown in the drawing I have indicated three such series, and it will be observed that the inner ends of the channels 8 of each series open into the interior of a sleeve or cylinder 9 which carries the hub 5, while the outer end of each channel 8 in each one of the series of channels discharges directly into the discharge passage 2.

70

Within the sleeve or cylinder 9 of the impeller 4 is a stationary cylinder or barrel 13 surrounding shaft 6 which rotates within it. This barrel 13 is provided with a series of openings in which are fitted short cylinders or tubes 12 that serve as nozzles and that lie in the same plane as the inner ends of the impeller channels 8. In the example of mechanism herein portrayed I have illustrated three series of nozzles 12 lying in three parallel vertical planes and situated coincident with respect to the inner ends of

the channels 8 belonging to the three series of such channels in the impeller 4, all as clearly represented in Fig. 1.

The barrel or cylinder 13 which carries the nozzles 12 is supported by the main casting 14 alongside of and if preferred integral with, the pump casing 1, said casting 14 serving as the casing for a centrifugal, turbine or similar pump having the function of drawing water through the suction 15 and delivering it in a steady stream to the nozzles 12. This latter supply pump is provided with a rotating impeller 16 secured on the main pump shaft 6, which impeller 16 discharges into the curved passages 17 and then through the passages between the vanes or blades 18 to the interior of the barrel or cylinder 13, whence the water passes, as already stated, through the nozzles 12. As the latter nozzles are stationary while the impeller 4 is rotating it will be obvious that the water will be caught by and projected into the channels 8 whenever said channels 8 pass the open ends of said nozzles 12, and thus there will be a succession of water plugs or pistons delivered into said channels. The provision of a multiplicity of nozzles arranged in several series has the effect of exposing a large surface of water to the air 30 to absorb the same in consequence of the injector-like action of the nozzles.

The air which is to be pumped enters the pump through the air inlet 11, coming from any point from which it is desired to draw air, and fills the interior of the chamber 19 and also the interior of the sleeve or cylinder 9 of the impeller 4, and thus fills the space around the nozzle-carrying barrel 13 and around the nozzles 12 so that it can readily pass into the interior of the channels 8 through the inner open ends of said channels. The air will find its way into the channels 8 whenever water is not entering said channels, and, therefore, since the delivery of the water to the channels is broken or interrupted whenever a blade 7 passes the open end of one of the nozzles 12 the air will at this moment have an opportunity to enter the channel, therefore each channel will be alternately entered by water and air, the water being injected by the pumping pressure from the centrifugal pump into the passages in such a way as to form successive moving plugs of fluid or liquid pistons between which are caught certain quantities of air in the manner explained, and thus there are air pistons between the water plugs. It will be obvious moreover with respect to the way in which the air finds its way into the interior of the device that the outwardly moving water plugs create a reduced pressure within the chamber 19 into which air is forced by atmospheric pressure.

The main pump shaft 6 is supported in suitable bearings 24 of any preferred con-

struction. On the shaft 6 is the belt pulley 10 for the application of a belting to drive the pump. The impeller 4 is kept air tight preferably by means of water seals 23 which receive water from any suitable source and deliver it to points on opposite sides of the groups of impeller vanes and around the central sleeve or cylinder 9 as shown in Fig. 1. Further the shaft 6 has stuffing boxes 20 and 21 of any desired or preferred form, each being provided with a water seal 22.

In the operation of my improved pump the multiple arrangement of nozzles in several series operating with an injector-like action serves to offer a large surface of water to the air, and draws the air in and mixes it with the water; so that not only are there formed water plugs and air plugs alternately in the several channels, but also there is this additional mixing of the air with the water, and thus the air is effectively pumped and a vacuum produced.

So far as the structural details are concerned, it is obvious that they may vary widely, and I reserve the liberty of making such changes in the exact construction as may be found necessary or desirable in order to promote the best results.

Having thus described my invention, what I claim as new and desire to secure by Letters Patent, is:—

1. In a centrifugal, turbine or similar pump, the combination of a main casing having a single discharge passage a rotary impeller having a plurality of radial series of channels, a stationary water passage having a plurality of radial series of outlets arranged in parallel vertical planes corresponding in number with and situated opposite to the inner ends of the said series of channels, which water outlets inject the water into the inner ends of the channels intermittently, centrifugal pumping mechanism for drawing water from a suction and delivering it into the water passage whence it emerges through the series of outlets, and means including a sleeve attached to the rotary impeller and an air chamber in communication with said sleeve for allowing air to enter the inner ends of the series of channels alternately with the admission of water plugs, whereby each channel is filled with a succession of water plugs and alternate quantities of air.

2. In a centrifugal or like pump, the combination of a main casing having a single discharge passage a rotary impeller, having a multiple arrangement of series of radial channels, a stationary water supply having a multiple arrangement of series of radial outlets arranged in parallel vertical planes corresponding in number with and situated opposite to the series of impeller channels, said outlets delivering water with an injector-like action into the inner ends of the

channels intermittently and offering a large surface to the air for the purpose of drawing in the air and mixing it with the water, and means including a sleeve attached to the 5 rotary impeller and an air chamber in communication with said sleeve for allowing air to enter the inner ends of the channels of the impeller between the water plugs which are formed in said channels, whereby each 10 channel is filled with a succession of water

and air pistons, together with centrifugal pumping mechanism for drawing water from a suction and delivering it into the stationary water passage.

In testimony whereof I affix my signature 15 in the presence of two witnesses.

FREDERICK RAY.
